CLAIM

The ornamental design for a board game, as shown and described.

DESCRIPTION

FIG. 1 is a top plan view of the board game;

FIG. 2 is a side view, all side views being identical.

FIG. 3 is a top plan view of another embodiment of the board game; and,

FIG. 4 is a top plan view of another embodiment of the board game.

The bottom of the game board is hereby disclaimed as forming no part of the claimed design since it is flat and devoid of surface ornamentation.
